C. H. GUNN

VOICE TRANSMITTING DEVICE

Filed June 20, 1923

INVENTOR.
Charles H. Gunn
BY *George J. Webster*
ATTORNEY

UNITED STATES PATENT OFFICE.

CHARLES H. GUNN, OF OAKLAND, CALIFORNIA.

VOICE-TRANSMITTING DEVICE.

Application filed June 20, 1923. Serial No. 646,524.

To all whom it may concern:

Be it known that I, CHARLES H. GUNN, a citizen of the United States, residing at Oakland, in the county of Alameda, State of California, have invented certain new and useful Improvements in Voice-Transmitting Devices; and I do declare the following to be a full, clear, and exact description of the same, reference being had to the accompanying drawings, and to the figures of reference marked thereon, which form a part of this application.

This invention relates to a device for throwing the human voice through the air for a greater distance than it will ordinarily carry, the principal object of the invention being to provide a device for the purpose which will take the place of the megaphone usually used, and which, instead of being held to the mouth by the speaker, will be in the form of a self supporting yet portable stand, having a mouthpiece toward which the speaker will direct his voice without the necessity of his having to place his mouth directly against the mouthpiece as is necessary with megaphones, but from which his voice will be carried to his audience clearly and with an increase in volume, as far away from the speaker, within reasonable limits, as may be desired, without the speaker having to raise his voice above a natural speaking tone.

My device is adapted for use in speaking to any public gatherings, whether in halls or auditoriums or in the open air, and relieves the speaker both from the voice and arm strain incident to the use of a megaphone.

As above intimated, the distance to which the voice may be thrown may be varied at the will of the speaker, and also the direction in which it will be projected relative to the speaker, within limits, may also be easily regulated and changed, without alteration of position on the part of the speaker.

The above and other objects I accomplish by means of such structure and relative arrangement of parts as will be fully evident from a perusal of the following specification and claim.

On the drawings, similar characters of reference indicate corresponding parts in the several views, in which:

- Fig. 1 is a perspective view of the device.
Fig. 2 is a vertical side section thereof.
Fig. 3 is a bottom plan view of the same.

In carrying out my invention in the preferred manner, I provide a base 1 mounted on three legs 2, each individually and swivelly mounted on and projecting downwardly from the base from between ears 3 thereon, clamping means being provided to hold the legs in any set position, such as for instance wing-nuts 4 on the swivel-pins 5 of the legs which pass through the ears.

Mounted on and projecting upwardly from the base is a casing or container 6, preferably of wood and rectangular in shape, and surmounted by a top piece 7 arranged to serve as a book or paper support or for like purposes. The base members 6, and top 7 form a complete enclosure.

Mounted in the casing a short distance from the top thereof and extending transversely therethrough from front to back is a tube 8 on one end of which, outside the casing, is fitted a transmitting horn 9 of suitable size and shape, and on the other end a receiving horn or mouthpiece 10. The tube 8 preferably has an upward bend intermediate its ends toward the member 10 so that the latter is facing somewhat upwardly and is thus in a good position to receive the voice from the mouth of the speaker, which would be ordinarily somewhat behind and above the mouthpiece.

Also the mouthpiece 10 preferably has a tube 11 of its own, slidably in the adjacent portion of the tube 8, so that the position of the mouthpiece relative to the casing may be adjusted to suit the convenience of different speakers.

Mounted on the base 1 inside the casing is an electric motor 12 which drives a horizontally disposed fan 13 thereabove. The motor and fan are enclosed in a hood 14 supported on the base and spaced from the walls of the casing. Above the fan the hood forms an inverted funnel 15 which terminates in a nozzle 16 projecting into the tube 8 and facing toward the horn 9.

The nozzle flares out somewhat toward its outer end, so as to prevent any possibility of there being a whistling sound at that point as the air emerges.

The base 1 below the motor is provided with orifices 17, a damper 18 being arranged thereunder so that the sizes of said orifices, through which air passes to the fan, may be regulated to suit.

The entire casing 6, about the hood and tube 8, is preferably filled with cotton 19 or

some similar material which will deaden any possible noise and vibration set up by the motor and fan.

The principle of operation of the device is that with the operation of the fan, a blast of air will be forced through the nozzle and out through the horn 9, which at the same time will create a suction at the mouthpiece.

Therefore the sound vibrations caused by the voice of a speaker talking adjacent the mouthpiece, even though at some little distance therefrom, will be drawn into the tube 8 toward the nozzle, and will then be thrown through the horn by and with the blast of air from the fan by and with the blast of air issuing therefrom, so that the voice will be audible at a considerable distance from the horn, this distance being governed by the velocity of the air blast and by its volume, which in turn are governed by the speed of the fan and regulation of the damper.

To suit persons of different heights who may speak into the device, it is only necessary to adjust the legs to raise the level of the mouthpiece and casing as a whole. If it is desired to throw the voice either higher or lower, only that leg under the side of the device on which the horn is mounted is raised or lowered, thereby similarly adjusting said

horn, and causing the outwardly issuing blast to be directed up or down.

From the foregoing description it will be seen that I have produced a device which substantially fulfills the objects of the invention, and while I have here shown and described a specific arrangement of parts, I reserve the right to make such deviations from this showing as do not form a departure from the spirit of the invention, as defined by the appended claim.

Having thus described my invention, what I claim as new and useful, and desire to secure by Letters Patent is:—

A live voice transmitting device comprising a tube having an enlarged transmitting end, and a receiving mouth-piece at its other end, said tube being freely open from end to end, and means for developing an air blast at a point removed from the tube and discharging it into the tube at a point intermediate the ends of the tube and in the direction of the transmitting end whereby sound waves of the voice will be drawn freely into and through the open tube and discharged forceably out of such transmitting end.

In testimony whereof I affix my signature.

CHARLES H. GUNN.
